UNITED STATES PATENT OFFICE.

DAVID A. CARDEN, OF HOUSTON HEIGHTS, TEXAS.

CLEANING DEVICE FOR WELLS.

1,259,721.

Specification of Letters Patent. Patented Mar. 19, 1918.

Application filed July 21, 1917. Serial No. 182,088.

To all whom it may concern:

Be it known that I, DAVID A. CARDEN, a citizen of the United States, residing at Houston Heights, in the county of Harris and State of Texas, have invented certain new and useful Improvements in Cleaning Devices for Wells, of which the following is a specification.

This invention relates to new and useful 10 improvements in a cleaning device for wells and is particularly adapted for the purpose of the washing out of the well screen after it has been set in the bore.

Well screens now in most common use are 15 formed of perforated pipe usually wrapped with screen wire, the turns of which are spaced apart and as the screen is lowered into the bore, the slits between the turns of wire become clogged and filled with sand 20 and dirt and after the screen is set it must be washed out by forcing water under pressure, down within the screen and through the slits between the turns of wire. Also after the screen has been in the well for a 25 time, the slits gradually become clogged up by particles of sand and detritus so as to restrict and some times entirely cut off the inflow of fluid. The object of this invention is to provide a device for the purpose 30 of washing out the screen when it has become, for any reason, clogged.

With the above and other objects in view, the invention has particular relation to certain novel features of construction, operation and arrangement of parts, an example 35 of which is given in this specification and illustrated in the accompanying drawings wherein:—

Figure 1 is a side elevation of the device 40 located within the screen.

Fig. 2 is a fragmentary vertical sectional view thereof.

Fig. 3 is a transverse sectional view taken on the line 3—3 of Fig. 2.

Fig. 4 is a transverse sectional view of a 45 packing ring employed.

Fig. 5 is a plan view thereof.

Fig. 6 is a transverse sectional view of a 50 form of washer employed, and

Fig. 7 is a plan view thereof.

Referring now more particularly to the drawings, the numeral 1 indicates a well screen which is formed of perforated pipe wrapped with suitable screen wire 2, the 55 turns of which are spaced apart. This screen

is set in the bore and there is usually a space 3 between the screen and the wall of the bore. The oil flows in through the slits between the screen wire 2 from the surrounding reservoir into the interior of the 60 screen. However, in setting the screen, the slits between the turns of wire often become clogged with sand and other detritus and before the oil can enter the screen, said

screen must be washed out and cleaned. For 65 the purpose of accomplishing this object I have provided a device which will now be described:—This device includes two sections of pipe 4 and 5 which are spaced apart and each of which is provided with a plu-

70 rality of perforations 6, said sections 4 and 5 being connected by means of a pipe section 7 provided with a plurality of small perforations 8, said section 7 being connected to the adjoining sections by the collars 75 9 and 10. Fitted over each of the sections 4 and 5 are the metallic washers 11 which are spaced apart. These washers fit closely around the respective sections and between them are the open packing rings 12 which

80 surround the respective sections 4 and 5 and are spaced therefrom. The end washers are secured on the section 4 by means of the respective collars 9, 9', which are screwed on the respective ends of said section and abut 85

against said washers and the end washers are secured on the respective ends of the section 5 by means of the collar 10 and the cap 10' which are screwed on the respective ends of said section 5. The device is let 90

down into the screen by means of a string of pipe 13 and water is then forced down through said string under pressure by means of a force pump located at the surface. The 95 perforations of the sections 4 and 5 have a greater capacity than those of the section 7 and a portion of the water passes through the first mentioned perforations and forces the packing rings 12 open causing them to expand against the inner walls of the screen

100 on all sides forming a water tight joint with said screen and preventing the passage of water between the screen and the sections 4 and 5. The remainder of the water passes through the orifices 8 provided in section 7 105 and out through the portion of the screen opposite said last mentioned section and passes thence along the space 3 and enters the screen above the section 4 below the section 5. This current of water being under 110

strong pressure washes out the slits between the turns of wire and as the device is gradually lowered, washes out and cleanses the screen. A tube 14 terminates below the cap 5 10' and passes up through the washer and its upper end is provided with an elbow 15 which passes out through the pipe 13 and terminates within the screen. The current of water passing downwardly and entering 10 the screen beneath the washer passes thence upwardly through said tube 14 and the current carries with it the free sand in the fluid within the screen underneath the washer.

As the device is lowered in the screen 15 from time to time the water pressure may be cut off or lowered so as to decrease the friction between the rings 12 and the screen 1 to prevent the wear of and injury to said rings.

20 What I claim is:

1. A device of the character described including a perforated pipe, an expandable member surrounding the same and adapted to be expanded by pressure within the pipe 25 25 through said perforations and a hollow tube passing through said pipe whose respective ends terminate outside of the pipe above and below said expandable member.

30 2. In a device of the character described, a perforated pipe section, a plurality of washers surrounding the same and spaced apart and expandable packing rings fitted loosely between said washers, also to be

readily expanded radially by fluid pressure 35 exerted through said perforations.

3. In a device of the character described, a perforated pipe section, a plurality of washers surrounding the same and spaced apart and expandable packing rings spaced 40 from the pipe and fitted loosely between said washers.

4. A device of the character described including a perforated pipe, expandable members surrounding the same and spaced apart, 45 each of said expandable members including a plurality of washers surrounding the pipe and spaced apart and expandable packing rings fitted loosely between said washers and spaced from said pipe.

5. A device of the character described including a perforated pipe, expandable members surrounding the same and spaced apart, each of said expandable members including a plurality of washers surrounding the pipe 55 and spaced apart and radially expandable, packing rings fitted loosely between said washers and adapted to be expanded radially by a fluid pressure exerted through the perforations of the pipe.

In testimony whereof I have signed my name to this specification in the presence of two subscribing witnesses.

DAVID A. CARDEN.
